GIUSEPPE CORBO, OF CAMDEN, NEW JERSEY

LOCK FOR WINDOWS AND DOORS

Application filed November 10, 1928. Serial No. 318,404.

This invention relates to an improvement in locks and has as one of its objects to provide a lock which, without alteration or adjustment, may be employed either upon 5 a window or upon a door for the purpose of locking the same.

Another object of the invention is to provide a lock which will be extremely simple in its construction and will serve effectually 10 to lock the door or window to which it is applied. In this connection it may be stated that it is well known that the ordinary lock comprises a lock casing and the lock parts therein, and also a keeper for the lock 15 bolt so that the lock is secured to one sash of a window and the keeper to the other sash, or the lock is secured to the door and the keeper to the door frame and therefore considerable time is ordinarily required in 20 installing such locks as a considerable number of screws must be employed to secure the parts in place and therefore the invention has as its object to provide a lock which will require but a single screw to secure it 25 in place upon a window sash and, where employed temporarily as a lock for a door, may be employed without the necessity of securing it in place through the medium of a screw.

30 Another object of the invention is to provide a lock which will be secure when adjusted to locking position and which will not require the use of keys or any other means for adjusting the same to lock or 35 release the window or door parts with which it is associated.

While the accompanying drawings and the description which is to follow, constitute a disclosure of the preferred embodiment 40 of the invention, it will be understood that various changes may be made within the scope of what is claimed.

In the accompanying drawing:

45 Figure 1 is a view in side elevation of the lock embodying the invention installed upon the upper and lower sashes of a window;

Figure 2 is a top plan view of the lock installed upon a door and door frame;

50 Figure 3 is a vertical front to rear sectional view through the lock installed upon

the upper and lower sashes of a window as shown in Figure 1;

Figure 4 is a vertical transverse sectional view taken substantially on the line 4-4 of Figure 5 looking in the direction indicated by the arrows; 55

Figure 5 is a view partly in top plan and partly in section of the lock, the parts being arranged to occupy a common plane, to better illustrate the construction and relationship of the parts and the structure; 60

Figure 6 is a view partly in top plan and partly in horizontal section illustrating the locking member of the lock; 65

Figure 7 is a plan view of the pawl which is associated with the locking member shown in Figure 6. 65

The lock embodying the invention differs materially from locks of the ordinary types inasmuch as it consists essentially of a combined attaching and detent member and a locking and pawl member which is associated therewith, and in the drawing the attaching and detent member is indicated in general by the numeral 1 and comprises a base plate 2 which is of the rectangular form shown most clearly in Figure 5 of the drawing and which is provided near its outer corners with struck up spurs indicated by the numeral 3 and the said base plate is also formed with an opening indicated by the numeral 4. The attaching and detent member further includes a substantially cylindrical head 5 which is formed integrally at 70

that end of the attaching plate opposite the end at which the anchoring spurs 3 are located, and, for a purpose to be presently described, the head 5 is formed axially with a cylindrical bore indicated by the numeral 6. Likewise for a purpose which will presently be pointed out, the head 5 is offset with respect to the plane of the attaching plate 2 so that one face of the plate occupies a plane substantially tangential to the surface of the said head, and the adjacent portion of the said surface of the head is formed with transversely extending teeth which are indicated by the numeral 7. It will now be observed, by reference to Figures 1 and 3 of the drawing, which figures illustrate the 75

100

application of the lock to the sashes of a window, that in applying the lock to the window, the plate 2 of the combined keeper and attaching member 1 is disposed against the inner face of the lower rail of the upper sash and the spurs 3 are caused to penetrate the wood of which the rail is formed, a securing screw 8 being fitted through the opening 4 and threaded into the rail so as to firmly secure the plate in place against the said inner face of the rail and with the lower side of the head 5 resting against the upper side of the said rail. In this manner the member 1 is securely anchored in place with the employment of but a single screw and the connection of the member with the said lower rail of the upper sash is a very secure one, it being observed by reference to Figures 1 and 3 that, when the upper and lower sashes are both closed, the outer side of the upper rail of the lower sash will engage against the inner face of the plate 2, and inasmuch as these faces of the rails are ordinarily correspondingly beveled as shown in the said Figures 1 and 3, the plate 2 will be securely confined between the rails when the sashes are, as stated, both in closed position.

The locking or restraining unit of the lock is indicated in general by the numeral 9 and the same includes a one-piece member 10 which constitutes an abutment to engage the upper side of the upper rail of the lower sash of a window, when the lock is applied upon a window, to prevent raising of the lower sash or lowering of the upper sash. The said member 10 comprises spaced side portions 11 and a connecting body portion 12 which extends between and is integrally connected with corresponding longitudinal edges of the side portions 11, the said edges of the said side portions and the said transverse web or connecting portion 12 being curved upwardly as indicated by the numeral 13, at one end of the member so as to provide a rounded surface and adapt this portion of the member to constitute a finger piece. The side portions 11 of the member 10 extend beyond the other end of the web or connecting portion 12 to provide pivot ears 14 which are formed with oppositely located openings 15, and these ears are disposed to straddle the head 5, when the unit 9 is assembled with the attaching and detent member 1, a pivot pin 16 being fitted through the bore 6 of the head 5 and having its projecting ends engaging in the openings 15, the member 10 being in this manner pivotally connected with the head 5 so that it may be swung to occupy the locking or restraining position shown in full lines in Figure 1 of the drawing or the inactive or released position shown in dotted lines in the said figure. That end of the connecting portion 12 beyond which the side portions 11

extend is formed with an upwardly and thence inwardly deflected flange 17 which constitutes a fulcrum for the pawl of the lock, which pawl is indicated in general by the numeral 18. The said pawl 18 is preferably formed of sheet metal and comprises an approximately rectangular body which is preferably longitudinally curved as shown in Figure 3 of the drawing and this body is provided with a downwardly extending flange 19 terminating in a branch 20 which extends in the direction of that end of the pawl which is to be engaged by the finger in releasing the lock. It will be observed by reference to Figure 3 that the flange 19 and its extended portion 20, which latter portion extends beneath and is spaced from the body 18, constitute means which is engaged with the fulcrum flange 17 to mount the member 18 for rocking movement upon the member 10, and in order that the pawl 18 may coact with the teeth 7 of the head 5, its end adjacent which the fulcrum 20 is located, is beveled to provide an engaging edge 21 which is designed to engage the teeth 7 in the manner clearly shown in Figures 1 and 3 of the drawing. In order that the pawl may be yieldably held in engagement with the teeth 7 of the head 5, a leaf spring 22 is secured at one end as at 23 by a rivet or the like to the fulcrum flange 17 and extends outwardly and in spaced relation to the connecting portion 12 of the member 10 and is curved away from the plane of the said member to bear at its free end portion against that side of the pawl 18 which is presented toward the said connecting portion 12.

From the foregoing description and by reference to Figures 1 and 3 of the drawing it will be evident that in using the lock in connection with the sashes of a window, the attaching plate 2 of the combined attaching and detent unit 1 is secured to the inner face of the lower rail of the upper sash in the manner previously described and it will be evident by reference to the said Figures 1 and 3 that, when the edge 21 of the pawl 18 is free from engagement with the teeth 7, it may ride in contact with the smooth surface of the head 5 above the said teeth and the unit 9 may be caused to assume the dotted line position shown in Figure 1 of the drawing. With the unit 9 in this position, the lower sash may be raised or the upper sash may be lowered, or both sashes may be adjusted as stated without any interference on the part of the unit 9. However when the sashes are both closed, the unit 9 may be swung downwardly and inwardly to assume the full line position shown in Figures 1 and 3 whereupon, in such movement, the edge 21 of the pawl 18 will ride over the teeth 7 of the head 5 of the detent unit 1 and engage against one of these teeth at the

time its connecting portion 12 assumes a position resting upon the upper side of the upper rail of the lower sash of the window whereupon the unit 9 will be locked in the full line position shown in Figures 1 and 3 and the lower sash will be restrained against any upward movement and the upper sash against any downward movement. In order to permit of raising of the lower sash or lowering of the upper sash, it is of course only necessary to depress the inner end of the pawl 18 to disengage its edge 21 from the teeth 7 of the head 5, whereupon the unit 9 may be swung bodily upwardly to the dotted line position shown in Figure 1 as previously described.

Figure 2 of the drawing illustrates the manner in which the device may be employed as a lock upon a door and from this figure it will be observed that in this use of the device, the attaching plate 2 of the attaching and detent member 1 is disposed against the inner side of the door frame and held in place by the engagement of the spurs 3 in the stile of said frame, the unit 9 being adapted to be swung into and out of position to engage against the inner side of the door in the closed position of the door. It will be evident that in this use of the device it may be employed without the necessity of using a securing screw such as the screw 8 or, if it is to be a permanent fixture, such a screw may be employed.

Having thus described the invention, what I claim is:

1. A locking device for doors, windows and the like, comprising a securing member adapted to engage a support, a restraining unit hingedly connected to said securing member, teeth carried by said securing member and a spring pressed latching means mounted wholly within the restraining unit and adapted to engage said teeth for locking said restraining unit in a set position upon said securing member.

2. A locking device of the class described comprising a securing member having an offset head, a locking unit pivotally connected upon said head, said locking unit comprising spaced side portions extending substantially parallel, said side portions connected by means of a body portion across the bottom thereof, said body portion provided with an upwardly extending flange, said head provided with teeth formed thereon and a pawl carried by said flange and engaging said teeth for locking said locking unit in a set position and said pawl being mounted within said side portions and being shielded thereby.

3. As a new article of manufacture, a locking device comprising a securing member, a restraining unit pivotally connected to the upper end of said securing member and being substantially U-shaped in cross

section, the body portion of said restraining unit being cut away at one end to provide a pair of spaced ears, the inner end of said body portion provided with an upwardly and inwardly deflected flange constituting a fulcrum, a pawl adapted to engage the upper end of said securing member and provided with a downwardly extending hook punched from the body portion of the pawl and fitting under said deflected flange, and spring means mounted upon said flange and engaging the under face of said pawl for yieldably holding the same in engagement with the upper end of said securing member.

4. A locking device comprising a securing member having a laterally extending enlarged head, a restraining unit formed from a blank sheet of material having substantially parallel side portions and a connecting body portion, the inner end of said connecting body portion provided with an offset flange constituting a fulcrum, a latching pawl having a hook portion overhanging said flange, spring means interposed between the flange and said pawl for yieldably holding the pawl in an operative position, said head provided with means for receiving the pawl and permitting the locking of said restraining unit in a set position with respect to said securing member, the outer end of said body portion and the upper edges of said side portions being shaped to wholly shield said latching member within the restraining unit.

In testimony whereof I affix my signature.
